US00D876222S

(12) **United States Design Patent** (10) **Patent No.:** **US D876,222 S**
Carr et al. (45) **Date of Patent:** **** Feb. 25, 2020**

(54) **PRODUCT PACKAGE FOR ABSORBENT ARTICLES**

(71) Applicant: **The Procter & Gamble Company**, Cincinnati, OH (US)

(72) Inventors: **Stevi Lee Carr**, Cincinnati, OH (US); **Brenda Marie Mahan**, Liberty Township, OH (US)

(73) Assignee: **The Procter & Gamble Company**, Cincinnati, OH (US)

(**) Term: **15 Years**

(21) Appl. No.: **29/653,226**

(22) Filed: **Jun. 13, 2018**

Related U.S. Application Data

(62) Division of application No. 29/592,693, filed on Feb. 1, 2017, now Pat. No. Des. 829,093.

(57) **CLAIM**

The ornamental design for a product package for absorbent articles, as shown and described.

DESCRIPTION

FIG. 1 is a perspective view of a product package for absorbent articles;

FIG. 2 is a front view of the package shown in FIG. 1;

FIG. 3 is a left side view of the package shown in FIG. 1;

FIG. 4 is a rear view of the package shown in FIG. 1;

FIG. 5 is a right side view of the package shown in FIG. 1;

FIG. 6 is a top view of the package shown in FIG. 1; and,

FIG. 7 is a bottom view of the package shown in FIG. 1.

Broken lines are included for the purpose of illustrating environment and form no part of the claimed design.

The shaded areas highlight what is being claimed whereas the non-shaded areas form no part of the claimed design.

1 Claim, 7 Drawing Sheets
